(57) **CLAIM**

The ornamental design for a mobile phone, as shown and described.

DESCRIPTION

FIG. 1 is a front view of the mobile phone in an unfolded state showing my new design.

FIG. 2 is a rear view of the mobile phone of FIG. 1.

FIG. 3 is a left side view of the mobile phone of FIG. 1.

FIG. 4 is a right side view of the mobile phone of FIG. 1.

FIG. 5 is a top view of the mobile phone of FIG. 1.

FIG. 6 is a bottom view of the mobile phone of FIG. 1.

FIG. 7 is a left front perspective view of the mobile phone of FIG. 1.

FIG. 8 is a right, front and bottom perspective view of the mobile phone of FIG. 1.

FIG. 9 is a front view of the mobile phone of FIG. 1 in a semi folded state.

FIG. 10 is a top front perspective view of the mobile phone of FIG. 1 in the semi folded state.

FIG. 11 is a top view of the mobile phone of FIG. 1 in a folded state; and,

FIG. 12 is a top rear perspective view of the mobile phone of FIG. 1 in the folded state.

The shade lines in the figures show contour.

The broken lines that are immediately adjacent to the claimed design represent the bounds of the claimed design, while all other broken lines, showing the remainder of the mobile phone, are directed to environment and are for illustrative purposes only; the broken lines form no part of the claimed design. In addition, the unshaded surfaces in FIGS. 1 and 7-10 that directly adjoin the outermost claimed solid line edges form no part of the claimed design.
